INDICATOR

William F. Reisiger, Flushing, N. Y., assignor to
The Hunter Illuminated Car Sign Co. Inc.,
Flushing, N. Y., a corporation of New York

Application May 9, 1936, Serial No. 78,749

7 Claims. (Cl. 40—33)

This invention relates to a novel and improved form of indicator, the novel features of which will be best understood from the following description and the annexed drawing, in which I have shown a selected embodiment of the invention and in which:

Fig. 1 is a diagrammatic view illustrating the use of the indicator in a train;

Fig. 2 is a view on an enlarged scale of one of the indicators, this view being taken from the right of Fig. 3;

Fig. 3 is a section on the line 3—3 of Fig. 2;

Fig. 4 is a section on the line 4—4 of Fig. 5;

Fig. 5 is a view on the line 5—5 of Fig. 4;

Fig. 6 is a fragmentary end view of the operating means.

For the purpose of illustration, I shall assume that the indicator is used on a vehicle, such as a subway car, and in Fig. 1, I have shown a train of three subway cars having boxes forming parts of the indicators. In the other figures I have shown details of a single indicator, and since they are duplicates, a detailed description of one will suffice for all.

Each box 1 is adapted to be placed in a wall of a car and is provided with oppositely disposed windows 2 and 3, one of which may open to the inside of the car and the other to the outside. Between these windows I place a barrel which may have two heads 4 and 5 connected by a plurality of rods 6 to form an open frame. The heads may be provided with shafts 7 and 8 so that the barrel may be rotated, and this rotation may be achieved by means of a motor 9 secured to one of the shafts, here shown as the shaft 8.

Referring momentarily to Fig. 1, it will be seen that each one of the indicators is provided with a motor and that these motors are connected in parallel to line conductors 10 in which is a switch 11 disposed at one end of the train so that the motors may all be operated together from that end of the train. It will be obvious that other switches may be added, for example at the other end of the train, by making suitable changes in the wiring, as known in the electrical art.

Stretched around the barrel and supported on the supports 6 is a web 12 having its ends secured to two spindles 13 and 14. The supports are spaced apart approximately equally and are disposed at equal distances from the axis of rotation of the barrel. The distance between any two supports is such that a portion of the web is presented substantially flat at one of the windows, and diametrically opposite to that portion another web portion is presented to the other win-

dow. These oppositely disposed portions will have the same designations thereon.

In the illustrated embodiment, I have shown four separate designations, which may for convenience be exemplified by "Queens Plaza", "Bowling Green", "180th Street", and "Franklin Avenue", and which have been abbreviated, respectively, in certain of the figures as "Q. P.", "B. G.", "180", and "F. A.". In Fig. 3, the two "Q. P." designations are displayed at the windows 2 and 3. If now the two spindles 13 and 14 are rotated so that the "Q. P." designation at the window 3 is rolled up on the spindle 14, the two "B. G." designations will appear at the windows 2 and 3. Continued winding would result in the "180" designations appearing and then the "F. A." designations. Opposite the spindles 13 and 14 is shown a portion 12' of the web which is blank, and after each four designations on the web a blank space will be provided to correspond with the idle space between the two spindles 13 and 14. The frequency of these blank spaces will obviously depend upon the number of supports 6, when the spindles 13 and 14 are used.

If desired, the two spindles 13 and 14 may be omitted and an endless web may be stretched around the drum having, in the illustrated embodiment, five pairs of designations, but the use of the spindles with the web wound thereon provides more flexibility, in that a larger number of designations may be employed.

Ordinarily, the indicator will be used for terminal designations and will be used on one car for an extended time on one route, so that the terminals need not be changed except at the end of the route. That is to say, all that will be necessary, for example, for an indicator used on a car running between Bowling Green and 180th Street is to make the change from the "B. G." 40 designations to the "180" designations.

If the car is to be used on another line with differently named terminals, then all that is necessary is to wind up one spindle 13 or 14 and unwind the other until the parts of the web carrying the desired designations are so placed on the barrel frame as to be seen at the windows 2 and 3.

For the purpose of thus rotating the spindles 13 and 14, a hand-operated crank 15 may be used, and this may be secured to a pinion 16 meshing with gears 17 and 18 upon the spindles 13 and 14. If necessary, a friction device may be used between each gear and the spindle operated thereby, to compensate for differences in speed caused by the different diameters of the rolls on the spindles. If the spindles 13 and 14 were to be 55

wound and unwound often enough, an electric motor could be used in place of the crank, but ordinarily this mechanism is used so seldom that a hand crank will serve the purpose.

5 In order to illuminate the designations which are presented to the windows 2 and 3, I illuminate the interior of the barrel frame as by means of a lamp 19 mounted within a reflecting cover 20 at one end of the box 1. I find that by selecting a 10 lamp of the proper candle power, and by using a reflector of proper characteristics, the light passing through the adjacent head 4 of the barrel frame may sufficiently illuminate the interior of the web so as to make the designations plainly 15 visible at the windows 2 and 3. The heads are preferably made open, as plainly shown in Fig. 4, and I have found that the lighting arrangement indicated will operate successfully without the formation of shadows or other undesirable 20 features.

For convenience of access to the interior thereof, the box 1 may be made in sections hinged together as at 21. The supports 6 are shown as 25 in the form of rods, although, if desired, they may be in the form of rollers and will be obvious to those skilled in the art.

While I have shown the invention as embodied in a specific form, it is to be understood that various changes in details may be made without 30 departing from the scope of the invention, as defined by the appended claims.

I claim:

1. An indicator comprising two oppositely disposed windows, a barrel rotatably mounted between said windows with its axis substantially parallel thereto, said barrel comprising two rotatable spindles parallel to said axis, a web having its ends secured to said two rotatable spindles and stretched around the barrel, whereby 40 the web will move with the barrel as it rotates to present different portions thereof at said windows, the portions presented at any one time at said windows having the same designations, and means to rotate said barrel.

45 2. An indicator comprising two oppositely disposed windows, a barrel rotatably mounted between said windows with its axis substantially parallel thereto, a web surrounding said barrel and rotatable therewith, whereby as the barrel 50 rotates, portions of said web will be presented at said windows, the portions presented at any one time carrying the same designations, means for rotating said barrel to bring different designations before the windows, and means to move the web around the barrel.

3. An indicator comprising two oppositely disposed windows, a barrel rotatably mounted between said windows with its axis substantially parallel thereto, a web surrounding said barrel 60 and rotatable therewith, whereby as the barrel

rotates, portions of said web will be presented at said windows, the portions presented at any one time carrying the same designations, means for rotating said barrel to bring different designations before the windows, portions of said web being transparent, whereby light may pass from the inside of the barrel through the web to illuminate the designations thereon, means to illuminate the web from the inside of the barrel, and means to move the web around the barrel.

4. An indicator comprising two oppositely disposed windows, a barrel rotatably mounted between said windows with its axis substantially parallel thereto, said barrel comprising two rotatable spindles parallel to said axis, a web having its ends secured to said two rotatable spindles and stretched around the barrel, whereby the web will move with the barrel as it rotates to present different portions thereof at said windows, the portions presented at any one time at said windows having the same designations, means to rotate said barrel, and means for rotating said spindles in unison to wind the web upon one spindle and to unwind it from the other.

5. An indicator comprising a frame in the form 25 of a barrel, means supporting said frame for rotation about its axis, said frame comprising a plurality of supports and two rotatable spindles, all extending parallel to said axis and substantially equally spaced about said axis and equally 30 spaced therefrom, a web extending around said supports and secured at its ends to said rotating spindles, whereby upon rotation of said spindles the web may move around said supports, means for rotating said spindles, and means for rotating 35 said frame about its axis.

6. An indicator comprising a frame in the form of a barrel, said barrel having two opposite heads connected by supports substantially equally spaced about the axis of the barrel and equally 40 spaced therefrom, a web stretched around said supports, a window disposed adjacent said supports, means for rotating said barrel about its axis to bring different portions of said web before said window, and means to move the web 45 around the barrel.

7. An indicator comprising a frame in the form of a barrel, said barrel having two opposite heads connected by supports substantially equally spaced about the axis of the barrel and equally 50 spaced therefrom, a web stretched around said supports, a box within which said barrel is mounted for rotation about its axis, said box having windows disposed on opposite sides of said barrel, means for rotating the barrel within the box 55 to bring different portions of said web before said windows, and means to move the web around the barrel.
